(57) **CLAIM**

The ornamental design for a base for a water closet, as shown and described.

DESCRIPTION

In a preferred embodiments, the nature of this product is as a plumbing fixture in the form of a base for a water closet. FIG. 1 is a left, top, front perspective view of a plumbing fixture according to my new design;

FIG. 2 is a left side elevational view thereof, the right side elevational view thereof being a mirror image of the left side shown;

FIG. 3 is a top plan view thereof;

FIG. 4 is a front elevational view thereof;

FIG. 5 is a top, left, front perspective view of another embodiment of a base suitable for use with the water closet having a more elongated bowl;

FIG. 6 is a left side elevational view thereof; the right side elevational view thereof being a mirror image of the left side shown;

FIG. 7 is a top plan view thereof; and,

FIG. 8 is a front elevational view thereof.

The broken line representations of openings in FIGS. 1, 3, 5 and 7 and interior structure in FIGS. 1, 3, 5 and 7 are for the purpose of illustration only, and form no part of the claimed design. The rear elevational and bottom plan views are not shown in the embodiments of FIGS. 1-8 since they are not seen in normal use.
